UNITED STATES PATENT OFFICE.

HENRY BEAGLE, JR., OF PHILADELPHIA, PENNSYLVANIA.

DESIGN FOR HAMES-TOP.

Specification forming part of Design No. 6,617, dated April 29, 1873; application filed April 4, 1873.

To all whom it may concern:

Be it known that I, HENRY BEAGLE, Jr., of the city and county of Philadelphia, State of Pennsylvania, have invented a Design for a Hame-Top, of which the following is a specification:

In the accompanying drawing, Figure 1 is a side view of a hame-top made in accordance with my design, and Fig. 2 a transverse section of the same on the line 1 2, Fig. 1.

The hame-top is of the general curved shape shown in Fig. 1, and terminates at the extreme upper end in a rounded projection, *a*. It is of a square or nearly square sectional form, and

is beveled throughout at the corners *b*, as best observed in the sectional view, Fig. 2.

I claim—

The design for a hame-top, substantially as described, and as represented in and by the accompanying drawing.

In testimony whereof I have signed my name to this specification in the presence of two subscribing witnesses.

HENRY BEAGLE, JR.

Witnesses:

THOMAS McILVAIN,
HUBERT HOWSON.
